(57) **CLAIM**

The ornamental design for a cable housing, as shown and described.

DESCRIPTION

FIG. 1 is a top perspective view of an ornamental design of a cable housing.

FIG. 2 is a top view of the cable housing shown in FIG. 1.

FIG. 3 is a side view of the cable housing shown in FIG. 1; and,

FIG. 4 is a front view of the cable housing shown in FIG. 1. The dot dash lines shown in the drawings represent indeterminate length and form no part of the claimed design.
